BENCH LIGHT

Norvin H. Franks, Chicago, Ill., assignor to Sturdi-Bilt
Steel Products, Inc., Chicago, Ill., a corporation of
Illinois

Application July 12, 1954, Serial No. 31,388

Term of patent 14 years

(Cl. D48—20)

To all whom it may concern:

Be it known that I, Norvin H. Franks, a citizen of the United States and a resident of the city of Chicago, county of Cook, State of Illinois, have invented a new, original, and ornamental Design for a Bench Light, of which the following is a specification, reference being had to the accompanying drawings forming a part thereof in which:

Figure 1 is a perspective view of a bench light embodying my new design;

Figure 2 is a top plan view of the bench light;

Figure 3 is a front elevation of the bench light;

Figure 4 is a side elevation of the bench light;

Figure 5 is a rear elevation of the bench light; and

Figure 6 is a bottom plan view of the bench light.

I claim:

The ornamental design for a bench light, substantially as shown.
